DORIS G. WILL, OF FORT WAYNE, INDIANA.

STERILIZING APPARATUS.

Application filed November 17, 1924. Serial No. 750,288.

This invention relates to improvements in sterilizing apparatus and the objects thereof are: first, to provide a sterilizer in conjunction with a heating means therefor and automatic controlling means for estopping the action of the heating means when the sterilizer reaches a predetermined temperature; second, to provide automatic means for draining the sterilizer when the 10 action of the heating means therefor is estopped; third, to provide a valve controlled filling means for the sterilizer in conjunction with automatic heating means therefor, which heating means is simultaneously thrown into action upon operation of the filling means; and fourth, to provide automatic means of supplying disinfectant to the sterilizer.

These objects are accomplished by the construction illustrated in the accompanying drawings, in which:—

Fig. 1 is a side elevation of a construction embodying the invention, parts thereof being broken away;

Fig. 2 is a transverse section on the line 2—2 projected from Fig. 1;

Fig. 3 is a detail view showing an elevation in central section with the sterilizer and the disinfectant supply means therefor;

Fig. 4 is perspective view of the electrical control means for the sterilizer.

The characters appearing in the description refer to parts shown in the drawings and designated thereon by corresponding characters.

The invention includes a sterilizer consisting of a vessel 1, the top of which is open, and the bottom of which has a drain pipe 2 leading therefrom, there being a 40 check-valve 3 for controlling the discharge from the vessel through the pipe. The valve has a pendant stem 4 that projects beyond the lower end of the pipe by which it is operated.

Within the vessel is removably positioned a group of vertical partitions 5 radially disposed and secured along their respective inner edges to a central pipe 6, the pipe being open throughout its length. The lower 50 ends of said partitions are cut away at their inner portions to accommodate the upward movement of the check-valve 3 in the lower part of the vessel, and between the wings below the lower end of the pipe 6 is positioned a cup 7, the upper end of which is open. A receptacle 8, for liquid, provided

with a discharge pipe 9 is inverted and positioned with its discharge pipe extending down through the pipe 6 into the cup 7, the discharge pipe having an outlet opening 10 60 therein at a point slightly below the top of the bowl. The vessel 1 has also an overflow pipe 11 that projects through the bottom thereof and is open throughout its length.

The sterilizer is mounted in a housing 12 and rests upon the base 13 thereof with its drain pipe 2 and overflow pipe 11 extending down through the base, and is supplied with water through a supply pipe 14 having a 70 manually operated valve 15 for controlling the flow therethrough.

On the base 13 surrounding the lower end of the vessel 1 is positioned an electrical heating coil 16 by means of which heat is applied to the sterilizer, and also a thermostat is positioned in the housing, and which consists of an electrical heating coil 17 that surrounds an expansion rod 18, the rod being rigidly secured in the top of the housing 75 and extending downwardly throughout the length of the coil and projecting loosely through the base 13. Beneath the base is a horizontally disposed lever 19 having a pivotal support at one end in a pendant bracket 20, its opposite end having an upturned hook 21. A screw 22 secured in the bottom of the base extends loosely through the lever 19, and a compression spring 23 is interposed between the head of the screw and 80 the lever and bears upwardly against the lever. The lower end of the expansion rod 18 bears upon the top of the lever in opposition to the action of the spring, so that the lever is moved downwardly against the 85 resistance of the spring more or less as the rod expands lengthwise, which expansion is caused by heat derived from the coil 17 when energized.

Upon the bottom of the base is mounted, in 100 guides 40 and 40', a longitudinally movable bar 24 having at one end thereof a pendant lug 25 engageable by the hook 21 on the lever 19 when the movable bar reaches its innermost position, and having at its opposite end 105 a head 26 engageable by a cam 27 that is rigidly attached to the valve 15 so that when the valve is turned to open position the bar 24 is moved inwardly into locked engagement with the lever. The bar 24 has rigidly secured thereto a pendant block 28 composed of insulating material and an electrical con-

tact plate 29 is secured on the block, which plate has engagement with a contact member 30, that depends from the bottom of the base of the housing, when the bar is in locked engagement with the lever. The contact plate 29 and the heating coil 16 are electrically united by a conductor 31, and the coil 17 of the thermostat is electrically united through the medium of a bolt 32 and conductor 33. The heating coil is electrically united with a terminal post 34 by means of a conductor 35, and the coil 17 of the thermostat is electrically united with another terminal post 36 by means of a conductor 37, said terminal posts being connected respectively by means of conductors 38 with a suitable source of electrical energy (not shown).

A retracting spring 39 has at one of its ends connection with a stud 44 on the block 28, and at its opposite end with a stationary guide 40 on the bottom of the housing, by means of which the bar 24 is moved to its outermost position. Also, a lever 41 pivoted in a stationary bracket 42 has a bifurcated arm 43 which is engaged with a stud 44 on the block 28, so that when the bar 24 is moved outwardly, the lever 41 is moved upwardly and lifts the valve 3 by engagement with the lower end of the stem thereof.

In the operation of the invention water is supplied to the vessel 1 through the supply pipe 14 by turning the valve 15 manually to the position shown in Fig. 1. When the valve is thus turned the cam 27 acts against the head of the bar 24 causing the bar to move inwardly so that its lug 25 passes the hook 21 on the lever 19. The extension of the spring 23 raises the lever so that the hook engages the lug 25 and thus arrests outward movement of the bar 24. When the vessel is filled with water, as is indicated by the overflow therefrom passing out through the pipe 11, the valve 15 is manually closed and the cam 27 is correspondingly moved out of engagement with the bar 24 while the bar is held locked in its innermost position and the plate 29 in electrical contact with the contact member 30, which plate and contact member function as an electrical switch for closing the electrical circuit through the coils of the heating member and the thermostat. While the switch is thus held in closed position, the coils are energized by the current passing therethrough, and the consequent heat of the heating member is imparted to the vessel 1 so that the temperature of its contents of water is raised, and simultaneously therewith the bar 18 of the thermostat is likewise heated by the action of its coil. As the temperature of the bar is raised, it becomes expanded lengthwise and bears downwardly upon the lever 19 which is moved to a stage sufficiently low as to cause its hook 21 to release its locked

engagement with the lug on the movable bar, which when thus released permits the bar to be moved outwardly to its normal position by the action of the spring 39. The electrical switch is opened by the outward movement of the bar and consequently the flow of current through the coils is shut off. Also, as the bar 24 is moved to its outer position, the lever 41 is raised and the valve 3 in the vessel is consequently opened which permits the heated water in the vessel to drain therefrom. By adjusting the screw 22 so as to increase or decrease the pressure of the spring 23 against the lever 19, and by adjustably raising or lowering the position of the expansion rod 18, the period of the release from locked engagement of the movable bar 24 may be more or less deferred and the water in the vessel accordingly retained therein until the desired temperature shall have been reached.

In utilizing the invention the objects to be sterilized, such for example, as tooth brushes, dental and other instruments and razor blades or other objects are placed in the vessel between the partitions and are therein subjected to the action of the water during the heating operation, and may be left to dry therein after the water is drained from the vessel, the drying of which is augmented by the lagging heat of the heating element.

Disinfectant is introduced into the vessel from the receptacle 8 which is filled with any suitable disinfectant in liquid form and which passes therefrom into the cup 7 when the level of liquid in the cup is lowered therein sufficiently as to admit air into the nozzle 7 through its opening 10. The flow of the liquid disinfectant into the cup is automatically stopped by the rise of liquid in the cup above the opening in the nozzle which precludes the entrance of air into the nozzle.

What I claim is:—

1. In apparatus of the class described, a vessel for containing liquid having a valve controlled drain outlet and an overflow outlet; a valve controlled supply pipe for filling the vessel with liquid; an electrical heating coil for the vessel; a spring resisted electrical switch; a latch member engageable with the switch and operable to hold the switch in closed position; an electrical thermostat having operable relation with said latch and connected in electrical circuit with said switch and heating coil; means in connection with the valve controlling the supply pipe engageable with the switch and operable to close the switch when the valve is turned open; means actuated by the switch operable to open the valve of the drain outlet when the switch is opened; and means for automatically supplying disinfectant in limited quantities to the vessel.

2. In apparatus of the class described, a vessel for containing liquid having a valve controlled drain outlet and an overflow outlet; a valve controlled supply pipe for filling the vessel with liquid; an electrical heating coil for the vessel; a spring resisted electrical switch; a latch member engageable with the switch and operable to hold the switch in closed position; an electrical thermostat having operable relation with said latch and connected in electrical circuit with said switch and heating coil; means in connection with the valve controlling the supply pipe engageable with the switch and operable to close the switch when the valve is turned open; and means actuated by the switch operable to open the valve of the drain outlet when the switch is opened. 35
3. In combination with a vessel having a valve controlled drain outlet and an overflow outlet; a valve controlled supply means for filling the vessel; an electrical heating means for the vessel including a switch therefor; a thermostatically controlled latch 40 for holding said switch in closed position means actuated by the valve on the supply pipe operable to close said switch; and means operable to hold the valve of the drain outlet open while said switch is open. 45
4. In apparatus of the class described including a vessel having a valve controlled drain outlet and a valve controlled filling means, an electric heater for the vessel, a thermostat including a second electric heater; a thermostat operated by said second heater, there being an electric circuit connecting said heaters in series; and a latch detained switch member controlling said circuit, and also the valve of said drain outlet, and having actuated relation with the valve 40 of said filling means, said thermostat having operable relation with the latch of said switch member. 50
5. An appliance of the class described comprising a vessel; a valve controlled means for supplying the vessel with liquid; a thermostat; an electrical heating means, affecting the vessel and thermostat including an electrical switch therefor; a latch operable to hold said switch in closed position, and controlled by said thermostat; and means for automatically closing said switch upon operation of said filling means. 55
6. An appliance of the class described comprising a vessel; a valve controlled means for supplying the vessel with liquid; a thermostat; an electrical heating means, affecting the vessel and thermostat including an electrical switch therefor; a latch operable to hold said switch in closed position, 60 and controlled by said thermostat; means for automatically closing said switch upon operation of said filling means; and means for automatically draining the vessel when said switch is opened. 65

In testimony whereof, I affix my signature.
